UNITED STATES PATENT OFFICE.

FREDERICK C. DAVIS, OF ST. JOSEPH, MISSOURI.

SEPARABLE SCARF-PIN.

1,302,773.

Specification of Letters Patent.

Patented May 6, 1919.

Application filed May 31, 1918. Serial No. 237,540.

To all whom it may concern:

Be it known that I, FREDERICK C. DAVIS, a citizen of the United States, residing at St. Joseph, in the county of Buchanan, 5 State of Missouri, have invented certain new and useful Improvements in Separable Scarf-Pins; and I do hereby declare the following to be a full, clear, and exact description of the invention, such as will enable others skilled in the art to which it appertains to make and use the same.

The present invention is directed to the provision of a scarf pin structure including detachably connected head and pin portions 15 whereby a plurality of different ornamental heads may be associated with a single pin portion for support thereby on a scarf.

It is the object of the present invention to provide an improved detachable connection 20 for the head and pin body of a scarf pin, which may be most readily manipulated to connect or disconnect the head with respect to the pin body, but which when the head is connected affords a firm securing thereof 25 to the head body, such readily manipulated structure being simple in nature whereby to permit an exceedingly low cost of manufacture and to insure durability and efficiency in continued use.

With the above and other objects and advantages in view, the invention resides more particularly in the novel combination, formation and arrangement of parts hereinabove described and particularly pointed out 35 in the appended claims.

In the accompanying drawings:

Figure 1 is a perspective view of a scarf pin having its pin body and head portions detachably connected in a manner embodying the present invention.

Fig. 2 is a sectional view through the detachable connection transversely of the axis of the pin body.

Fig. 3 is a perspective view of the attaching end of the pin body.

Referring now more particularly to the accompanying drawings, there is shown the head of a scarf pin including a base plate 5 which may carry a stone or other ornament 10, and secured to the rear face of this base plate at one side thereof is one end of a spring strip 7 extending across the base plate and provided adjacent its secured end 15 with a transverse channel 8 in its inner face, formed by bowing the metal of the strip outwardly.

The pin body for association with this head structure comprises an ordinary wire shank 9 sharpened at one end to engage in the scarf fabric or other support, and this shank is freely movable through the channel 8 of the spring strip whereby it may be held by said strip against the back plate 5. The other end of the shank 9 is bent laterally and then inwardly at 10 in hook shape and the free extremity of the bill of this hook shaped portion is bent laterally from the plane of the hook shaped portion, to form a stop finger 11, while the bight of the hook shaped portion is offset laterally in the direction of the finger 11. When the head and pin body portions are connected as shown in Fig. 1, the bill of the hook shaped portion 10 is engaged between the free end of the spring strip 7 and the plate and resiliently pressed by said spring strip against the plate, the finger 11 and offset bight portion preventing sliding movement of the head on the pin body by abutment with the lower side of the spring strip, and the head 20 is thus attached to the pin body at two points in a manner effecting a firm securing.

To detach the head from the pin body, it is merely necessary to swing the strip 7 upwardly to provide clearance for the stop finger 11, and then to slide the pin body through the channel 8, and the attachment of a head to the pin body may be effected in a ready manner.

An exceedingly simple means has thus been provided for detachably connecting the head and pin body of a scarf pin, and thus a plurality of head members may be associated with a single pin body, procuring a 95 considerably economy in avoiding the necessity of providing a pin body for each head member, and also procuring a decided convenience to the wearer in traveling, since one or more of the head members may be 100 conveniently stored, or carried in the pocket without danger of injury or damage by projecting pin bodies.

To prevent loss or theft of the pin when worn in the scarf, a pin projection 12 is 105 formed on the lower edge portion of the base plate 5, which extends transversely of the main pin body shank 9 and which is adapted to engage in the scarf to prevent direct upward movement of the pin body in normal 110 relative position of the pin and scarf, it being noted that in detachment it is necessary

to move the scarf inwardly from the lower portion of the head member of the pin, to provide clearance for the pin projection 12.

What is claimed is:

- 5 1. In a separable scarf pin, the combination with a head, of a spring clip secured to the head and a pin body removably engaged with the clip and bodily removable from the head, said pin body including portions en-
- 10 gaged with the clip in a way to prevent sliding movement of the pin body with respect to the head, said spring clip being shiftable against its spring action to permit removal of the pin body therefrom and from the head and re-application of the pin body to the clip and the head.
- 15 2. The combination with the head portion of a scarf pin, of a pin body bodily removable therefrom and having one end portion formed in hook shape with the ex-
- 20 tremity of its bill extending laterally from the plane of the hook to provide a stop finger and a spring clip member secured to the head portion for urging the hook por-
- 25 tion of the pin body against the head portion, and engageable by said stop finger to prevent relative movement of the head portion longitudinally of the pin body.
- 30 3. The combination with the head portion of a scarf pin, of a pin body bodily removable therefrom and including a shank having one end formed in hook shape with

the extremity of the bill of the hook extending laterally from the plane of the hook to provide a stop finger and a spring strip 35 having one end secured to the head portion and provided on its inner face adjacent its securement to the head portion with a transverse channel adapted to receive the shank of the pin body, the bill portion of the hook 40 being engageable between the other end of the spring strip and the head portion.

4. A separable scarf pin including a head, a pin body bodily removable therefrom, and a spring clip carried by the head and including portions formed to produce a channel in which the pin body is engaged with its sides engaging the sides of the channel to prevent lateral movement of the pin body 50 with respect to the head, said pin body in- including portions engaging the spring clip in a way to prevent longitudinal movement of the pin body with respect to the head, said clip being shiftable against its spring action to permit removal of the pin body 55 therefrom and from the head and re-application of the pin body to the clip and head.

In testimony whereof, I affix my signature, in the presence of two witnesses:

FREDERICK C. DAVIS.
